Primary Examiner — Mehri F Bajou1(57) **CLAIM**

The ornamental design for a fast sling puck game set, as shown and described.

DESCRIPTION

FIG. 1 is a perspective view of a fast sling puck game set showing my new design in an exploded state comprising a game board and three gates;

FIG. 2 is a perspective view thereof, showing the board portion and the gate 1 separately for ease of illustration;

FIG. 3 is another perspective view thereof, showing the board portion and the gate 2 separately for ease of illustration;

FIG. 4 is another perspective view thereof, showing the board portion and the gate 3 separately for ease of illustration;

FIG. 5 is a front elevation view of the fast sling puck game set shown separately from the gates for the ease of illustration;

FIG. 6 is a back elevation view thereof;

FIG. 7 is a left elevation view thereof;

FIG. 8 is a right elevation view thereof;

FIG. 9 is a top plan view thereof; and,

FIG. 10 is a bottom plan view thereof.

1 Claim, 10 Drawing Sheets(56)
